his Attorney.

UNITED STATES PATENT OFFICE.

WILLIAM AUGUSTUS KILMER, OF DE KALB, ILLINOIS, ASSIGNOR TO THE AMERICAN STEEL AND WIRE COMPANY OF NEW JERSEY, OF HOBOKEN, NEW JERSEY, A CORPORATION OF NEW JERSEY.

GATE-LATCH.

1,202,733.

Specification of Letters Patent. Patented Oct. 24, 1916.

Application filed July 6, 1916. Serial No. 107,801.

To all whom it may concern:

Be it known that I, WILLIAM A. KILMER, a citizen of the United States, and resident of De Kalb, in the county of Dekalb and State of Illinois, have invented certain new and useful Improvements in Gate-Latches, of which the following is a specification.

This invention has relation to gate latches for fastening swinging gates in closed position, and more particularly relates to gate latches for use on gates arranged to swing horizontally both inwardly and outwardly into open position and in some cases to gates which also tilt vertically at one end to lift the swinging end of the gate, a type known as tilting gates.

One object of the invention is to provide a gate latch of improved construction having novel means whereby the gate latch is engaged by the gate when the gate is moved into closed position and is automatically fastened by the closing movement of the swinging gate so as to secure the gate in closed position.

Another object of the invention is to provide a gate latch having novel means whereby the latch is secured in gate holding position until released manually and is readily released when the gate is to be opened.

Another object of my invention is to provide a gate latch having novel means for maintaining the various parts of the latch mechanism in coacting relation and for preventing the latch fastening means from moving into inoperative positions.

A further object of the invention is to provide a gate latch having means whereby a vertically tilting gate engages with and is held in closed position by the latch by swinging the gate horizontally into closed position while permitting free vertical tilting movement of the gate while locked against horizontal opening movement.

A still further object of my invention is the provision of a gate latch having the novel constructions, combinations and arrangements of parts shown in the drawings, to be more fully described hereinafter and to be particularly pointed out in the appended claims.

The invention will be more clearly under-

stood by reference to the accompanying drawings in which—

Figure 1 is an elevation showing a swinging gate having a gate latch thereon embodying the novel features of my invention; Fig. 2 is a side elevation, on a larger scale, of the gate latch forming this invention; Fig. 3 is a plan of the gate latch of Fig. 2 with the latch fastening in gate latching position; and Fig. 4 is a plan, partly in section and similar to that of Fig. 2 with the gate latching mechanism shown in open or gate releasing position.

In the accompanying drawings the numerals 2 and 3 designate vertical posts which are fixed by their lower ends in upright position in the ground. Located between the posts 2 and 3 is a gate which is fastened at one end to the post 3 by means of clamps 4, 4, and a pivotal support 5, the gate swinging about the axis of the pivot support 5. The gate, which is of the horizontally swinging and vertically tilting type, includes an articulated frame formed of vertical members 6 and 7 pivotally connected at the ends thereof to the ends of horizontal members 8 and 9. A woven wire fabric 10 is employed to fill the rectangular space formed by the members 6, 7, 8 and 9 of the gate frame. The fabric 10 is secured at one end to the frame member 6 and the opposite end of the fabric is fastened to the auxiliary member 11 of the frame, the member 11 being adjustably secured to the frame member 7 by hook bolts 12.

Mounted on the post 2 so as to operatively engage with the vertical member 6 of the swinging end of the gate is the novel gate latching mechanism forming my invention. The latch mechanism as shown comprises two forked latches 13 each having tines 14, 14, which are adapted to embrace the vertical member 6 of the gate to fasten the gate in closed position. The latches 13 are pivotally secured to flanged latch supports 15 by pivot pins 16 and the latch supports are rigidly secured to the post 2 by means of flanges 17 and bolts 18. When desired a U-bolt may be employed in lieu of the flanges 17 and bolts 18 to fasten the supports to the post 2. Each latch 13 has an integral rearwardly extend-

ing arm 19 and the outer or swinging end of the arm 19 has projections or lugs 20 thereon as is clearly shown in Figs. 3 and 4. Also formed on the rear end of the latches 16 is a 5 boss having a concave edge 22, the plane of this boss being below the plane of the lower surface of the arm 19.

Pivotedly mounted on each latch support 15 is a keeper 23. Each keeper has a pivot 10 pin 24 formed integrally therewith or otherwise fastened to the keeper to turn therewith. The pivot pin 24 for the upper keeper projects downwardly through an opening in its support 15 and the pivot pin 24 for the lower 15 keeper 23 projects upwardly through an opening in its support 15. The projecting ends of the pivot pins 24 extend into the ends of a hollow shaft 25 conveniently formed of a piece of pipe, and transversely 20 extending pins 26 in the registering holes in the pivot pins 24 and ends of the pipe shaft 25 fasten the keepers to the shaft so that when one keeper is turned the other turns also.

25 The keeper 23 has a lug or ear 27 thereon with an aperture in the lug through which the rear end of the arm 19 of the forked latch projects. The posts 28 forming the ends of the aperture or slot in the lug 27 30 engage with the projections 20 on the rear end of the arm 19 to maintain the forked latch in gate securing position.

By reference to Fig. 3 it will be seen that when in latch holding position (or that 35 shown in Fig. 3) the posts 28 of the lug 27 on the keeper 23 are in a vertical plane between the plane of the axis of the latch pivot pin 16 and that of the pivot pin 24 of the keeper 23, and that the lugs 20 on 40 the end of the arm 19 of the latch interlock with the posts 28 of the lug 27 on the keeper so as to prevent the keeper's being turned by the forked latch into position to release and permit the forked latch to swing into 45 gate releasing position.

When the keeper 23 is turned on its pivot (manually) into the position shown in Fig. 4, or into its other and opposite angular position, the arm 19 will swing freely out 50 of the slot in the lug 27 and will not engage with or be held by the posts 28 so that the latch is released and the gate can be swung into open position, the gate swinging in one direction when the keeper is moved into the 55 position shown in Fig. 4, and swinging in the other direction when the keeper is moved into its opposite angular position relative to the position as shown in Fig. 1.

When my improved gate latch mechanism 60 is applied for use with a tilting gate like that shown in the drawings, the swinging end of the gate can be tilted upwardly without interference of the latch mechanism, in such case the post 6 moving upwardly 65 between the tines 14, 14, of the forked latches

13. The rear end of the boss on the latch 13, through which the latch pivot pin 16 extends, has a concave curved surface 22 of a radius which clears the point 29 formed by the intersection of the concave curved surfaces 30 and 31 on the keeper 23 when the latch is in gate holding position, and the curved surfaces 30 and 31 on the keeper 23 are of a radius which will permit the latch 70 to swing on its pivot without engagement 75 of the keeper with the curved surfaces 32 and 33 on the boss of the latch 13. The curved surfaces 30 and 32 and also the curved surfaces 31, 33, coact to prevent the keeper's being rotated to such an extent as 80 to prevent automatic turning of the keeper by the arm 19 on the latch 13 when the gate swings into open position, and in swinging into closed position automatically engages 85 with and swings the latch from the position shown in Fig. 4 into that shown in Fig. 3.

The operation of my improved gate latch will be readily understood. Assuming the gate to be in closed position, with the latch 90 13 and keeper 23 in the position shown in Fig. 3, the member 6 of the gate will be embraced by the tines 14 of the latch as is shown in Fig. 1. When in this position the gate is locked against opening movement but 95 the swinging end of the gate is free to tilt or move upwardly, the gate shown being of the tilting type. The projections 20, 20, on the latch arm 19 engage with the posts 28 on the lug 27 of the keeper 23 and prevent 100 turning movement of the keeper by the latch when the keeper is in the central position shown in Fig. 3. When it is desired to open the gate the keeper 23 is turned from the position shown in Fig. 3 into that shown 105 in Fig. 4. As the top keeper 23 is connected to the bottom keeper 23 by the pipe shaft 25 the keepers turn in unison. When the keeper is in the position shown in Fig. 2 any opening movement of the gate will 110 cause the gate member 6 to engage with the tines 14 of the latch and a slight swinging movement of the latch 23 will move the rearwardly extending arm 19 forming an integral part of the latch, to bring one or the 115 other of the projections 20 on the end of the arm into interlocking engagement with one or the other of the posts 28 forming part of the upwardly extending lug 27 on the keepers and prevent further turning movement 120 of the keeper and opening movement of the latch and gate. After the keeper 23 is moved manually into the position shown in Fig. 4 the swinging end of the gate can be moved 125 as the member 6 of the gate swings the latch 13 from the position shown in Fig. 3 into that shown in Fig. 4, the end of the arm 19 swinging freely out of the slot in the now angularly extending lug 27. The curved surfaces 30 and 32 or the curved surfaces 130

31 and 33 on the pivot pin boss of the latch and on the edge of the keeper, prevent or limit its turning movement and maintain the keeper in position so that interference with the closing movement of the latch by the keeper is avoided and overcome. When the open gate is being moved into closed position, the member 6 of the gate will engage with the tines 14 of the latch 13 and swing the latch from the position shown in Fig. 4 into the position shown in Fig. 3. In moving into the position of Fig. 3 the arm 19 on the rear end of the latch enters the slot in the lug 27 on the keeper and the adjacent projection 20 on the end of the arm 19 engages with the adjoining post 28 on the keeper and swings the keeper from the angular position shown in Fig. 4 into the central and latch holding position shown in Fig. 3. The gate is in this way again locked in closed position, as further opening movement of the gate will be prevented by engagement of the arm 19 on the latch with the post 28 forming part of the lug 27 on the keeper, the projections 20 on the end of the arm 19 interlocking with the posts 28 to fasten the latch in gate holding position.

The advantages of my invention will be apparent to those skilled in the art. The apparatus is simple, is strong and durable, and will not require frequent repairs.

Modifications in the construction and arrangement of the apparatus may be made without departing from my invention. The gate latch mechanism may be applied to a gate which swings in but one direction instead of swinging inwardly and outwardly. The gate need not necessarily be of the vertically tilting type. A single latch and keeper may be employed instead of two latches as shown in the drawings, and other variations in the arrangement of the parts may be made without departing from my invention as defined in the appended claims.

45 I claim:

1. In a gate latch, the combination with a swinging gate of a forked latch adapted to engage with and hold the gate in closed position and having an integral arm thereon, a support on which the latch is pivotally mounted, and a keeper pivotally mounted on the latch support and having means engaging with said arm to lock the latch in gate securing position, said keeper being automatically moved by said arm into locking position when the latch is moved by the closing movement of said gate.

2. In a gate latch, the combination with a swinging gate of a forked latch adapted to engage with and hold the gate in closed position and having an integral arm thereon, a support on which the latch is pivotally mounted, a keeper pivotally mounted on the latch support and having means engaging with said arm to lock the latch in gate se-

curing position, said keeper being automatically moved by said arm into locking position when the latch is moved by the closing movement of said gate, and coacting means on said latch arm and keeper arranged to prevent opening movement of said latch by opening movement of the closed gate.

3. In a gate latch, the combination with a swinging gate of a forked latch adapted to engage with and hold the gate in closed position and having an integral arm thereon, a support on which the latch is pivotally mounted, a keeper pivotally mounted on the latch support and having means engaging with said arm to lock the latch in gate securing position, said keeper being automatically moved by said arm into locking position, coacting means on said latch arm and keeper arranged to prevent movement of said latch into unlocked position by opening movement of the gate, and coacting means on the keeper and latch for preventing movement of the keeper when the latch is in gate releasing position.

4. In a gate latch, the combination with a swinging gate of a forked latch adapted to engage with and hold the gate in closed position and having an integral arm thereon, a support on which the latch is pivotally mounted, a keeper pivotally mounted on the latch support and having means engaging with said arm to lock the latch in gate securing position, said keeper being automatically moved by said arm into locking position when the latch is moved by the closing movement of said gate, and a lug on said keeper having a slot therein arranged to receive the end of the arm on said latch to lock the latch in gate holding position.

5. In a gate latch, the combination with a swinging gate of a forked latch adapted to engage with and hold the gate in closed position and having an integral arm thereon, a support on which the latch is pivotally mounted, a keeper pivotally mounted on the latch support and having means engaging with said arm to lock the latch in gate securing position, said keeper being automatically moved by said arm into locking position when the latch is moved by the closing movement of said gate, a lug on said keeper having a slot therein arranged to receive the end of the arm on said latch to lock the latch in gate holding position, and projections on the ends of said arm engaging with the sides of said slot to prevent opening movement of the latch by movement of the closed gate.

6. In a gate latch, the combination with a swinging gate of a plurality of forked latches, said latches being adapted to engage with and secure the gate in closed position, and having an integral arm thereon, supports on which the latches are pivotally mounted, keepers pivotally mounted on the latch supports, said keepers being rotatable

relative to said latches and having means engaging with said arms to lock the latches in gate securing position, and means connecting the keepers arranged to move said keepers in unison, said keepers being arranged to automatically engage with said arms and thereby move into locking position

when the latch is moved into gate holding position by the closing movement of said gate.

In testimony whereof I have hereunto set my hand.

WILLIAM AUGUSTUS KILMER.
